UNITED STATES PATENT OFFICE.

LUKE E. SCAFE, OF LEEDS, COUNTY OF YORK, ENGLAND.

BOOT OR SHOE.

SPECIFICATION forming part of Letters Patent No. 416,861, dated December 10, 1889.

Application filed April 14, 1887. Serial No. 234,854. (No model.) Patented in England November 2, 1886, No. 14,090.

To all whom it may concern:

Be it known that I, LUKE EARNSHAW SCAFE, of Leeds, in the county of York, England, have invented an Improvement in Soles or Heels 5 for Boots and Shoes, of which the following is a specification.

Letters Patent for this invention were granted to me in Great Britain on November 2, 1886, No. 14,090.

10 Before my invention rubber and leather had been associated in soles or heels, the rubber being in the form of plugs or strips within openings in the leather.

15 My present invention relates to the combination, with the leather sole having openings through the same, of a sheet of rubber having projections that fill the openings in the leather, and which sheet or layer of rubber forms a water-proof middle sole and at the 20 same time secures the plugs or projections of rubber, so that they cannot become loose or fall away from the leather outer sole.

25 In the drawings, Figure 1 is an elevation of a shoe with my improved sole. Fig. 2 is an inverted plan, and Fig. 3 is a longitudinal section.

30 The boot or shoe represented at *a* is provided with any ordinary heel and sole, as represented at *f*, Fig. 3, and *b* represents the leather sole, having perforations in it, as shown at *d*, which perforations may be of any desired size, shape, or number.

35 The sheet *e* of rubber is of the desired size to form a layer or middle sole between the soles *b* and *f*, and upon the same are the rubber plugs or projections *c*, corresponding in size, shape, and position to the openings in the sole *b*, so that the leather sole *b* can be applied to the rubber either before or after the

rubber has been placed upon the sole *f*, and 40 the parts may be cemented together, and it is preferable to secure the sole *b* to the boot or shoe by sewing or by nails or rivets.

For some kinds of shoes the combined rubber and leather sole may extend the whole 45 length of the shoe without any separate heel; but I have shown a heel in Figs. 1 and 2, which may be of any desired character.

In all instances the sheet or middle sole of rubber renders the boot or shoe sole impervious 50 to water, and the projection *c* is held firmly by the sheet of rubber and cannot become loose or drop out from the opening in the leather.

I am aware that rubber plugs with flanged 55 upper ends have been inserted in boot-heels, and that rubber plugs upon a ring of rubber have been secured to a heel by a perforated metal plate and screw. In my improvement the rubber insole with studs and the leather 60 sole with openings are attached around their edges to the uppers and form a water-proof combined rubber and leather sole.

I claim as my invention—

The combination, in a boot or shoe, with 65 the outer leather sole having openings through the same, of a rubber sheet overlying the outer sole and forming an intermediate water-proof sole between the outer and inner soles of the boot or shoe, and having numerous 70 rubber studs or projections formed integral with the rubber sheet and passing through and filling the openings in the outer sole, substantially as set forth.

L. E. SCAFE.
